US00D933654S

(12) **United States Design Patent** (10) **Patent No.:** **US D933,654 S**
Chung et al. (45) **Date of Patent:** **** Oct. 19, 2021**

(54) **DISPLAY DEVICE**

(71) Applicant: **Samsung Display Co., Ltd.**, Yongin-si (KR)

(72) Inventors: **Yung Bin Chung**, Yongin-si (KR); **Kee Hyun Nam**, Seoul (KR); **Jun-Sang Lyu**, Seoul (KR); **Eui Ri Cho**, Suwon-si (KR); **Kyung Hyun Ko**, Hwaseong-si (KR); **Jun Il Kwon**, Suwon-si (KR); **Sung-Hee Lee**, Anyang-si (KR); **Woo-Jong Lee**, Seongnam-si (KR); **Hyun Joo Lee**, Cheongju-si (KR); **Ho Jung Lee**, Seoul (KR); **Jae Beom Choi**, Suwon-si (KR)

(73) Assignee: **Samsung Display Co., Ltd.**, Yongin-si (KR)

(**) Term: **15 Years**

(21) Appl. No.: **29/643,664**

(22) Filed: **Apr. 10, 2018**

(30) **Foreign Application Priority Data**

CLAIM

The ornamental design for a display device, as shown and described.

DESCRIPTION

FIG. 1 is a front perspective view of a first embodiment of the display device according to the present design; FIG. 2 is a front view of the first embodiment; FIG. 3 is a rear view of the first embodiment; FIG. 4 is a left side view of the first embodiment, with the right side view being a mirror image; FIG. 5 is a top view of the first embodiment, with the bottom view being a mirror image; FIG. 6 is a rear perspective view of the first embodiment;

FIG. 7 is another front view of the first embodiment; FIG. 8 is another rear view of the first embodiment; FIG. 9 is a front perspective view of a second embodiment of the display device according to the present design; FIG. 10 is a front view of the second embodiment; FIG. 11 is a rear view of the second embodiment; FIG. 12 is a left side view of the second embodiment, with the right side view being a mirror image; FIG. 13 is a top view of the second embodiment, with the bottom view being a mirror image; FIG. 14 is a rear perspective view of the second embodiment; FIG. 15 is another front view of the second embodiment; FIG. 16 is another rear view of the second embodiment; FIG. 17 is a front perspective view of a third embodiment of the display device according to the present design; FIG. 18 is a front view of the third embodiment; FIG. 19 is a rear view of the third embodiment; FIG. 20 is a left side view of the third embodiment, with the right side view being a mirror image; FIG. 21 is a top view of the third embodiment, with the bottom view being a mirror image; FIG. 22 is a rear perspective view of the third embodiment; FIG. 23 is another front view of the third embodiment; FIG. 24 is another rear view of the third embodiment; FIG. 25 is a front perspective view of a fourth embodiment of the display device according to the present design; FIG. 26 is a front view of the fourth embodiment; FIG. 27 is a rear view of the fourth embodiment; FIG. 28 is a left side view of the fourth embodiment, with the right side view being a mirror image; FIG. 29 is a top view of the fourth embodiment, with the bottom view being a mirror image; FIG. 30 is a rear perspective view of the fourth embodiment; FIG. 31 is another front view of the fourth embodiment; FIG. 32 is another rear view of the fourth embodiment; FIG. 33 is a front perspective view of a fifth embodiment of the display device according to the present design; FIG. 34 is a front view of the fifth embodiment; FIG. 35 is a rear view of the fifth embodiment; FIG. 36 is a left side view of the fifth embodiment, with the right side view being a mirror image; FIG. 37 is a top view of the fifth embodiment, with the bottom view being a mirror image; FIG. 38 is a rear perspective view of the fifth embodiment; FIG. 39 is another front view of the fifth embodiment; FIG. 40 is another rear view of the fifth embodiment; FIG. 41 is a front perspective view of a sixth embodiment of the display device according to the present design; FIG. 42 is a front view of the sixth embodiment; FIG. 43 is a rear view of the sixth embodiment; FIG. 44 is a left side view of the sixth embodiment, with the right side view being a mirror image; FIG. 45 is a top view of the sixth embodiment, with the bottom view being a mirror image; FIG. 46 is a rear perspective view of the sixth embodiment thereof; FIG. 47 is another front view of the sixth embodiment; and, FIG. 48 is another rear view of the sixth embodiment. The broken lines, showing images displayed on a main screen on the front side and showing images on a sub-screen on the rear side, represent environment and form no part of the claimed design. All other even-dash broken lines and any

unshaded regions within them, represent portions of the display device and form no part of the claimed design.
